United States Patent Office.

HOMER RIGGS, OF OXFORD, CONNECTICUT.

Letters Patent No. 74,851, dated February 25, 1868; antedated February 12, 1868.

IMPROVEMENT IN BOOT AND SHOE-SOLES.

The Schedule referred to in these Letters Patent and making part of the same.

TO ALL WHOM IT MAY CONCERN:

Be it known that I, HOMER RIGGS, of the town of Oxford, in the county of New Haven, in the State of Connecticut, have invented new and useful Improvements in Attaching and Detaching Over-Soles to Boots and Shoes; and the following is a full, clear, and exact description of the same, reference being had to the accompanying drawings, making a part of this specification, in which—

Figure 1 represents a boot-foot with the over-sole in its place.

Figure 2 shows the bottom of a shoe, with the fixtures secured, and the over-sole off.

Figure 3 shows the over-sole.

The object of my invention is to protect the wear of the shoe-sole, and consists in the arrangement of a toe and rear plate, firmly secured to the bottom of the shoe, in such form as to admit of a lift or plate of metal being sprung in, covering the ball of the sole, and also taken out when desirable, by any one, without removing any of the fastenings.

To enable others to make and use my improvement, I will describe it more fully, referring to the drawings.

A toe-piece, A, made of sheet metal, cut or pressed out, in the form shown in figs. 1 and 2, is firmly fastened to the bottom of the sole at the toe, and also another piece of metal, B, is secured in the same manner to the sole C, in the hollow of the shoe, leaving the ball D uncovered, as seen in fig. 2, when desired. To protect the wear of the leather sole, D, I have taps or plates of steel, E, so shaped that the ends, e e, will enter in under the pieces A and B by bending the tap or plate E outward, so as to shorten the distance between the points e e, and the sole of the boot or shoe bent inward, so as to lengthen the space between the reverse points d d of the pieces A and B, thus enabling the wearer to put the over-soles E in or take them out, at pleasure.

What I claim as new, and desire to secure by Letters Patent, is—

The toe-piece A and rear plate B, as constructed, and the manner of inserting the over-sole E and securing it for wear, so that it can be sprung in or out, substantially as and for the purposes herein set forth.

HOMER RIGGS.
